RIFLE REST

2 Sheets-Sheet 1

FIG. 1

Fig. 2

FIG. 4

A diagram showing a coiled spring assembly. The spring is mounted on a horizontal frame. Several callouts point to different parts of the assembly, each labeled with a number: 14, 20, 18, 16, 14, 12, 44, 10, 42, 48, and 48. The numbers 48 and 48 are repeated, likely indicating two legs of the frame. The number 10 points to a vertical support leg.

RIFLE REST

Russell S. Kester, Linwood, Pa.

Application December 20, 1956, Serial No. 629,535

2 Claims. (Cl. 89—40)

This invention relates generally to rifle rests, and more particularly has reference to an improved rest to be used in obtaining maximum stability of the firearm while one is aiming the weapon at stationary targets or game, and to be further used in relieving one of the necessity of supporting the weight of the weapon, so as to still further promote accuracy of aiming while at the same time providing increased comfort for the user.

Rifle rests, to be employed during the aiming and firing of the weapon, are not of course new in and of themselves. However, it has been noted, in connection with the prior art devices, that in some instances said devices have been lacking in adaptability for affording a proper support for the rifle at locations spaced along the length of the weapon, such as to insure to the maximum accurate aiming and firing thereof.

It has been noted in connection with the devices of the prior art that the same are not, in some instances, fully collapsible and portable, and have tended to be excessively complicated and heavy in construction.

It has further been noted, in connection with gun rests previously conceived, that elevation and lowering of the muzzle of the weapon in many instances has involved the full supporting of the weapon at its stock by the user, and has further involved the necessity of the user's swinging the stock end upwardly or downwardly to effect swinging movement of the muzzle end of the rifle in a vertical plane for the purpose of locating the sights directly on the target. This of course has tended to produce inaccuracies, in view of the fact that in many instances it is difficult for the user to swiftly pivot the weapon, when following the practice described, to the desired position and then hold the same in position for firing.

Still further, in the devices heretofore conceived of which I have knowledge, adjustments of the rifle position have not been capable of being effected with the desired speed. Reference is here had to a main adjustment of the rifle position at a selected angle of inclination or at the horizontal, said main adjustments being of course necessary, and being followed by minute adjustments, effected by the marksman through moving the weapon itself upon the rest for the purpose of locating the sight on the target.

The main object of the present invention is to provide a rifle rest which will have none of the deficiencies above noted.

A more specific object is to form the rest in a manner such that it can be manufactured readily, at low cost, from inexpensive components, with the rest mainly comprising relatively light but strong rods, either tubular or of solid construction.

Another object is to provide a rifle rest in which the support for the rear end of the stock will be of flexible material, so that the stock support can yield within a predetermined range in a downward direction if it is desired to swing the muzzle upwardly, said flexible support at the same time still providing a firm base on which the stock will rest.

2

Still another object is to provide a rifle rest in which the main adjustment of the rifle position can be effected swiftly merely by pivoting of a front leg frame upon the main frame or bench of the device, with the adjustment being retained by engagement of the front leg frame in the ground.

Still another object is to form a device of the character described which, though affording a two-point support for the weapon, and characterized by its ready adjustability in the manner previously described herein, will still be collapsible to an almost wholly flat condition to permit its storage or transportation in a very small area.

Other objects will appear from the following description, the claims appended thereto, and from the annexed drawing, in which like reference characters designate like parts throughout the several views, and wherein:

Figure 1 is a top plan view of a rifle rest according to the present invention, a supported rifle being shown in phantom lines, with the marksman seated in position to fire the rifle, the marksman also being shown in dotted outline;

Figure 2 is a side elevational view of the device and of a supported rifle in which phantom lines show the support and the rifle in one position of adjustment;

Figure 3 is a perspective view of the rifle rest in which a portion of the rifle stock support member has been broken away;

Figure 4 is an enlarged transverse sectional view substantially on line 4—4 of Figure 2;

Figure 5 is a transverse sectional view, on the same scale as Figure 4, taken substantially on line 5—5 of Figure 2 with the rifle removed;

Figure 6 is a detail sectional view, still further enlarged, of the connection of the brace means to the rear leg frame; and

Figure 7 is a perspective view of the device collapsed for storage or transportation.

The rest 10 constituting the invention is adapted to support a rifle R at the rear end of the stock, and also at a location adjacent the forward end of the stock as shown in Figure 2. The rest may appropriately be considered as comprising four main, relatively pivoted components, namely a main frame or bench, of a front leg frame, a rear leg frame, and a brace assembly. Each of these will be described in turn, in detail, hereinafter.

The main frame has been generally designated 12, and has the general form of a rectangle elongated in a fore-and-aft direction and disposed either in a horizontal plane as shown in full lines in Figure 2, or in any of various adjusted planes inclined to a comparatively slight degree from the horizontal, as shown in dotted lines in the same figure of the drawing.

The main frame may be composed of tubular or solid rod stock, and includes elongated, parallel, side rails 14 straight from end to end thereof and integral or otherwise made rigid at their rear ends with a transversely extending rear end member 16, perpendicular to the length of the side rails.

The main frame is of open-center construction, and at its rear end, the open center of the main frame is closed by a rectangular flexible rear stock support member 18, which can be formed of canvas or similar material, said member extending the full distance transversely of the main frame and being laced at its periphery, as at 20, to the side rails 14, the rear end member 16, and a cross brace 22 of the main frame located intermediate the ends of the main frame and extending transversely between and fixedly connected to the respective side rails.

The support member 18 provides a yieldable but nevertheless suitably firm support for the rear end of the rifle stock, so that if necessary one can press the rear end

of the stock downwardly to a slight degree, for the purpose of lining up the sights with the targets.

The front leg frame has been generally designated at 24, and may appropriately be considered as being of inverted U-shape, including at its upper end a horizontally, transversely extending front support member for the rifle R, about which is circumposed a length of rubber hose or similar material, providing a supporting sleeve 28 on which the rifle rests. Integral with the opposite ends of the member 26 are elongated, depending legs 30 which diverge in a downward direction and terminate at their lower ends in sharpened, ground-penetrating points or anchors 32. Transversely bracing the front leg frame is a cross brace 34 fixedly connected between the divergent end portions of legs 30.

Adjacent its upper end, frame 24 pivots upon the front end of the main frame 12, about a horizontal, transverse axis parallel to the front support member 26. The pivotal connection of frame 24 to frame 10 can be effected in any of various ways. In the illustrated example, the forward extremities of side rails 14 are welded to coaxial hinge sleeves 36 extending toward each other at the front end of the main frame, and receiving a hinge rod 38, the ends of which are fixedly engaged in aligned openings 40 formed in legs 30 adjacent the upper ends of the legs.

Alternatively, the ends of rod 40 could be welded or otherwise fixedly secured to the back surfaces of legs 30.

At its rear end, main frame 12 is supported upon a rear leg frame generally designated at 42. This is in the form, in a preferred embodiment, of an inverted isosceles triangle, and is formed with a horizontal, transverse, tubular hinge bar or cross piece 44 at its upper end, sleeved on and rotating upon a pin 46 the ends of which underlie side rails 14 adjacent member 16. Rigid with and extending downwardly from the ends of the sleeve or tubular cross piece 44 are downwardly convergent rear legs 48, welded or otherwise fixedly joined at their convergent ends and terminating, at said convergent ends thereof, in a tubular opening having welded therein one end of a connector pin 50 (Figure 6), the lower end of which extends downwardly from and beyond the convergent ends of legs 48.

The bracing assembly comprises an elongated, straight brace rod 52, which at its forward end is rigid with a tubular, transverse hinge sleeve 54 rotating upon the midlength portion of rod 40 (see Figure 5). At its rear end, the brace rod 52 receives a pin 56 which is welded in and projects out of the brace rod, terminating in a pointed, downwardly angled extension 58 engageable in the ground G.

Welded to and extending upwardly from the rear end of rod 52 is a sleeve 60, having a threaded opening in which is engaged a clamping screw 62. Pin 50 is receivable in sleeve 60 as shown in Figure 6, and is fixedly engaged in the sleeve by means of the clamping screw.

In use of the device, it may normally be maintained in a collapsed position in which the mentioned main components thereof are disposed almost in coplanar relation, whereas to permit storage or transportation of the rest in a relatively small area, having a height or width little greater than the thickness of any of the rods previously described herein. This is shown to advantage in Figure 7. It will be noted that front leg frame 24 pivots about the axis defined by rod 38 into substantially coplanar relation to the main frame 12. Bracing assembly 52 similarly pivots about the rod 38, into a position underlying the main frame, with the bracing assembly disposed between the main frame and the front leg frame. The rear leg frame pivots forwardly about the axis defined by pin 46, also into underlying relation to the main frame, extending between the main frame and the bracing assembly. The final result is that the entire device is collapsible into an almost wholly flat condition.

In setting up the rest, the front and rear leg frames are pivoted outwardly to their Figure 2 positions, with the

bracing assembly 52 extending at an acute angle to the main frame, after which pin 50 is engaged fixedly in sleeve 60. The rest has a three-point support upon the ground, afforded by the pointed tips 32 at the front end of the device, and by the tip 58 at the rear end of and located medially between the opposite sides of the device.

In this position of the parts, the front rifle support member projects upwardly above the plane of the main frame as shown in Figure 2, and supports the fore part 10 of the rifle stock. The rear end of the rifle stock is supported upon the flexible member 18, and the user seats himself at right angles to the rifle rest with the rear leg frame of the structure between his legs.

The weapon will now be supported by the device at points longitudinally spaced on the weapon, with the front point of support being designated at 64 and being disposed well forwardly of the trigger. It will be readily perceived that if it is desired to elevate the muzzle, one may shift the weapon forwardly so that the stock rises to a short extent upon the front rifle support member, thereby elevating the muzzle instantly. Elevation of the muzzle to a slight degree can also be obtained by a slight downward pressure on the rear end of the stock, tending to depress the rear support member 18. Lowering of the muzzle is effected by retraction of the weapon to the desired extent.

If it is desired to effect a change in the main adjustment of the rifle position, as for example from the full to the dotted line positions of Figure 2, the tip 58 at 30 the lower end of rear leg frame 42 can be disengaged from the ground, and the rear leg, brace and main frame can be swung about the axis defined by the rod or pin 38, thereby changing the angularity of the front leg frame relative to the ground surface, correspondingly 35 raising or lowering the front end of the main frame relative to the rear end of the main frame and vertically adjusting sleeve 28. In the illustrated example, the front end of the main frame has been adjusted upwardly by moving the tip 58 to the phantom line position from the 40 full line position of Figure 2. The tips 32 remain engaged in the ground surface, as is readily apparent, when the adjustment is made.

It is believed apparent that the invention is not necessarily confined to the specific use or uses thereof described above, since it may be utilized for any purpose 45 to which it may be suited. Nor is the invention to be necessarily limited to the specific construction illustrated and described, since such construction is only intended to be illustrative of the principles of operation and the 50 means presently devised to carry out said principles, it being considered that the invention comprehends any minor change in construction that may be permitted within the scope of the appended claims.

What is claimed is:

55 1. A rifle rest comprising an elongated, approximately horizontal main frame; front and rear leg frames pivotally connected to the front and rear ends, respectively, of the main frame for movement about axes extending transversely of the main frame between collapsed and main-frame-supporting positions, the front leg frame projecting upwardly above the main frame when in its supporting position to support a rifle at a forward location thereon, the main frame including means adjacent the rear end thereof for supporting the rear end of the rifle said means embodying a flexible support member extending transversely over the main frame adjacent the rear end and secured to the sides and rear end of said main frame; and brace means connected to the front end of the main frame at one end of the brace means, the other end of the brace means having a detachable connection to the lower end of the rear leg frame, said brace means comprising an elongated rod pivotally connected to the front end of the main frame for swinging movement about the axis of the pivotal connection of the front leg frame, said detachable connection of the

brace rod to the rear leg frame comprising a sleeve extending upwardly from the brace rod, the rear leg frame including a depending pin engageable in said sleeve to the main frame.

2. A rifle rest comprising an elongated, approximately horizontal main frame; front and rear leg frames pivotally connected to the front and rear ends, respectively, of the main frame for movement about axes extending transversely of the main frame between collapsed and main-frame-supporting positions, the front leg frame projecting upwardly above the main frame when in its supporting position to support a rifle at a forward location thereon, the main frame including means adjacent the rear end thereof for supporting the rear end of the rifle; and brace means connected to the front end of the main frame at one end of the brace means, the other end of the brace means having a detachable connection to the lower end of the rear leg frame, said brace means comprising an elongated rod pivotally connected to the front end of the main frame for swinging movement about the axis of the pivotal connection of the front leg frame to the main frame, said detachable connection of the brace rod to the rear leg frame comprising a sleeve extending

upwardly from the brace rod, the rear leg frame including a depending pin engageable in said sleeve, the brace rod being formed rearwardly of the sleeve with a ground-penetrating point, the front leg frame including transversely spaced, ground-penetrating points co-operating with the point of the brace rod in providing a three-point support for the rifle rest.
